FURNACE FIRE BOX AND ARCH STRUCTURE

John C. Chapple, St. Louis, Mo.

Original application May 29, 1931, Serial No. 540,948. Divided and this application August 28, 1934, Serial No. 741,850.

6 Claims. (Cl. 122—68)

This invention relates to furnace fire box and arch structures, and has for its primary object and purpose to provide the fire box with water circulating elements extending therethrough having means for supporting an arch wall composed of refractory bricks or units of standard form and with the rear upper end of the wall downwardly curved or inclined to deflect the course of flow of the products of combustion into contact with the fire door, side and crown sheets of the fire box.

The novel feature of my invention in this respect is more particularly characterized by an improved type of water circulating element extending through the fire box upon which the arch is supported so constructed as to obviate the formation of steam holding or retaining pockets.

The present application is a division of my co-pending application Serial No. 540,948, filed May 29, 1931, and has more particular reference to the novel construction of the water circulating elements or tubes which extend through the fire box and have vertically elongated end sections with parallel side walls adapted to open through the door sheet of the fire box.

With the above and other objects in view, the invention consists in the improved furnace fire box and arch structure as will be hereinafter more fully described, illustrated in the accompanying drawing, and subsequently incorporated in the subjoined claims.

In the drawing wherein I have disclosed a simple and practical embodiment of the essential features of my improvements, in which similar reference characters designate corresponding parts throughout the several views:

Figure 1 is a vertical fragmentary sectional view illustrating an embodiment of the invention as applied to a locomotive fire box, said section being taken substantially on the line 1—1 of Figure 2, and

Figure 2 is a transverse section taken through the same substantially on the line 2—2 of Figure 1.

Modern high powered locomotives are provided with boiler fire boxes of appreciably greater length than those heretofore used in standard locomotive boiler construction, and if the conventional type of arch is proportionately extended rearwardly towards the fire box door sheet, the space between the top of the arch and the crown sheet is too greatly restricted. If the comparatively short arch is used, the products of combustion pass over the rear end of the arch forwardly to the boiler flues together with consid-

erable fine coal unignited or only partially consumed and are not brought into contact with the fire door sheet and rear portions of the side sheets and crown sheet of the fire box. This results in inadequate steam production and uneconomical consumption of fuel. In a co-pending application for patent filed of even date here-with, I have disclosed an improved arch structure for use in connection with relatively long fire boxes having its upper rear end embodying means for deflecting the products of combustion downwardly towards the fuel bed and in contact with the rear side sheets, fire door sheet and crown sheet of the fire box and which obviates undue restriction of the space between the top of the arch and the crown sheet. In order to enable this arch to be used in conjunction with water circulating tubes and siphons of conventional form, I have disclosed in said application, refractory tile or brick constituting the upper end of the arch of a certain novel form and construction.

I propose, by means of my present invention to accomplish this same general result with the use of an arch composed wholly of refractory bricks or units of standard form.

In the drawing wherein I have illustrated the essential feature of my invention as applied to a locomotive fire box, 5 designates the fire door sheet of the rear end of the fire box, 6 the flue sheet at the forward end thereof, 7 the fire tubes or flues, 8 the crown sheet, and 9 the throat sheet extending downwardly from the flue sheet in rearwardly offset relation thereto. In these respects, the boiler fire box is of conventional form, and it will therefore, be understood that the boiler water surrounds and is in direct contact with the outer surfaces of these metal walls or sheets of the fire box.

Obliquely inclined water circulating tubes extend longitudinally through the fire box from the throat sheet 9 to the fire door sheet 5. As herein shown, each of these tubes includes a forward section 10 opening at its lower end through the throat sheet 9, said tube section having a lower portion of somewhat greater radius than the upper portion thereof to provide longitudinally extending shoulders 11 on each side of said tube section. The upper end of the tube section 10 on its lower side, is longitudinally curved as indicated at 12, the shoulders 11 extending throughout this curved part of the tube in concentric relation thereto.

The upper portion of the tube at this curved section 12 gradually merges into the vertically

elongated or flattened upper section 13 of the tube which opens at its upper end through the fire door sheet 5 adjacent to the crown sheet 8. The walls of the lower curved portion 12 of the tube and the shoulders 11 are gradually merged into the opposite side walls of the flattened tube sections 13 so as to avoid the formation of internal steam holding or retaining pockets in the tube walls.

10 As shown in the drawing a series of such water circulating tubes in any desired number may be arranged in transversely spaced relation through the fire box and upon the shoulders 11 of these spaced tubes, the arch forming brick or tile of refractory material, indicated at 14, are supported at their opposite ends, thus preventing the direct passage of the products of combustion upwardly between the tubes in this portion of the fire box and causing the same to flow longitudinally along and in contact with said tubes in the rear ends of the arch wall. The bricks 14 are of a standard form widely used in such locomotive arches having upper and lower curved surfaces with the lower concave surfaces thereof 25 opposed to the fuel bed. As seen in the drawing, by reason of the curved rear end portions of the shoulders 11 of the supporting tubes, the brick forming the rear end of the arch wall will be successively supported at different angles and together form a rearwardly extending downwardly curved or inclined deflecting section so that the gases and products of combustion will be directed by said upper rear end of the arch wall rearwardly and downwardly toward the fuel 30 bed and into contact with the fire door sheet 5. Any solid fine particles of fuel carried in suspension by the gases are thus returned to the zone of intense heat where they will be ignited. Thus, by causing the products of combustion to 35 directly contact with and flow upwardly along the fire door sheet 5, a maximum percentage of the heat units will be utilized in the conversion of the water into steam. Also, the products of combustion are thereby caused to come into direct contact with the rear end portion of the crown sheet 8, as well as with the portions 13 of the water circulating tubes having a relatively 40 extensive wall area. This further increases the maximum extraction of heat from the burning 45 gases and the generation of steam in the boiler.

50 While any preferred means may be employed for the purpose of retaining the rear downwardly inclined brick 14 of the arch upon the supporting shoulders 11, for this purpose, I prefer to weld or otherwise permanently secure to the opposite sides of the water circulating tubes the short lugs or trunnions indicated at 15 which effectively prevent the downward sliding movement of the fire brick.

55 I have herein shown one embodiment of the essential features of my invention, but it is to be understood that the same might also be incorporated in various other alternative structure forms, and I accordingly reserve the privilege of 60 adopting all such legitimate changes therein as may be fairly incorporated within the spirit and scope of the invention as claimed.

65 What is claimed is:—

70 1. In combination with a locomotive boiler fire box, water circulating tubes extending longitudinally through the fire box between the door sheet and throat sheet thereof, each of said tubes including a vertically elongated end section 75 having parallel side walls integrally con-

nected at their upper and lower edges, said end section of the tube opening through the door sheet of the fire box between the door opening and the crown sheet, and the remaining portion of said tube being of substantially cylindrical form and connected with the throat sheet of the fire box, and an arch wall supported substantially wholly upon said cylindrical portions of the water circulating tubes and terminating at its rear end at the juncture between said cylindrical and elongated portions of the tubes and in spaced relation from the fire box door sheet.

2. In combination with a locomotive boiler fire box, water circulating tubes extending longitudinally through the fire box between the door sheet and throat sheet thereof, each of said tubes having a vertically elongated section opening through the door sheet of the fire box between the door opening and the crown sheet, the remaining portion of said tube being of substantially cylindrical form and connected to the throat sheet of the fire box, and an arch wall supported upon said cylindrical portions of the tubes and extending therebetween.

3. In combination with a locomotive boiler fire box, water circulating tubes extending longitudinally through the fire box between the door and throat sheets thereof, each of said tubes having a vertically elongated end section opening into the door sheet and having a substantially cylindrical section opening through the throat sheet of the fire box, and an arch wall supported upon the cylindrical portions of the tubes and being substantially coextensive with said cylindrical portions of the tubes and terminating at the juncture thereof with the vertically elongated tube sections.

4. In combination with a locomotive boiler fire box, water circulating tubes extending lengthwise in the fire box between the door and throat pipes thereof, each of said tubes having a vertically elongated section at one end and a substantially cylindrical section at its other end emerging from the vertically elongated section, and an arch wall supported substantially wholly upon the cylindrical portions of the tubes and extending throughout the lengths of the cylindrical portions thereof.

5. In combination with a locomotive boiler fire box, water circulating tubes extending lengthwise in the fire box and having vertically elongated end sections opening through the door sheet and having substantially cylindrical opposite end sections extending from the vertically elongated sections and opening through the throat sheet of the fire box, and an arch wall supported upon the cylindrical sections of the tubes and extending throughout the lengths of the said cylindrical sections.

6. In combination with a locomotive boiler fire box, water circulating tubes extending longitudinally through the fire box between the door sheet and throat sheet thereof, each of said tubes including a vertically elongated end section opening through the door sheet and having opposite end portions of substantially cylindrical form extending from the vertically elongated sections and opening through the throat sheet of the fire box, and an arch wall supported substantially wholly upon said cylindrical portions of the tubes and terminating at its rear end at the juncture between the cylindrical and the vertically elongated sections of the tube.
